Primary Examiner — Michael A Pratt*Assistant Examiner* — Michelle E Wilson(74) *Attorney, Agent, or Firm* — Stoll Keenon Ogden PLLC;
Rebecca Ann Krefft(57) **CLAIM**

The ornamental design for a foot and ankle stretcher, as shown and described.

DESCRIPTION

FIG. 1 is a front perspective view of a foot and ankle stretcher showing my new design;

FIG. 2 is a rear perspective view thereof;

FIG. 3 is a right side elevation view thereof, the left side view being a mirror image of the right side view;

FIG. 4 is a right side elevation view thereof shown in an alternate and second setting position, the left side view being a mirror image of the right side view;

FIG. 5 is a right side elevation view thereof shown in an alternate and third setting position, the left side view being a mirror image of the right side view; and,

FIG. 6 is a front elevation view thereof shown in an alternate and folded position.
